UNITED STATES PATENT OFFICE.

ERNEST J. WILLIAMS, OF ST. LOUIS, MISSOURI.

COMBINED FAN AND EYE-SHADE.

1,108,649.

Specification of Letters Patent. Patented Aug. 25, 1914.

Application filed December 8, 1913. Serial No. 805,344.

To all whom it may concern:

Be it known that I, ERNEST J. WILLIAMS, a citizen of the United States, residing at St. Louis, in the State of Missouri, have invented certain new and useful Improvements in Combined Fans and Eye-Shades, of which the following is a specification.

My invention relates to a combined fan and eye shade.

10 The object of the invention is to provide a simple and inexpensive fan and eye shade which is provided with means whereby it may be securely attached to the brim of a hat so as to lie parallel therewith.

15 A further object is to provide the handle of the fan with a suitable socket into which may be slipped the shank of a longitudinally extending clip; the free end of the clip extending toward the free end of the handle to permit the entrance of a hat brim thereunder between the clip and the handle.

20 A further object of the invention is to let the shank of the clip into the handle flush with the surface thereof.

25 A further object is to form the handle edge of the fan blade on a curve to correspond with the curvature of the hat brim.

These objects I accomplish by the construction shown in the accompanying drawing, in which:

Figure 1 is a perspective of my improved fan and eye shade applied to a hat brim. Fig. 2 is a similar view of the fan and eye shade removed from the brim. Fig. 3 is a longitudinal vertical section on line 3—3, Fig. 2. Fig. 4 shows the clip separately. Fig. 5 is a view showing another way of securing the shank of the clip directly to the handle.

40 A designates the blade or body of the combined fan and eye shade provided with a suitable handle A'. The blade and its handle may be formed of any suitable material, but I prefer some cheap material, such as cardboard, for the blade, and wood for the handle. This permits of the printing of advertising and pictorial matter on the blade or body.

45 The handle edge of the blade A is concaved, as at a, to correspond to the curvature of the brim of a hat B so that it may underlie the same from end to end of the blade, as shown in Fig. 1, and present a symmetrical appearance.

55 The fan handle A' is provided with a longitudinal oblong recess a' in its upper

side at about its middle and the inner end of the recess a' is crossed by a countersunk plate a² so as to form a socket into which may be slipped the flat shank c of an arched 60 clip C formed of a flat steel spring, the free end of the clip being curved upwardly, as at c', and resting upon the handle toward its free or outer end.

The free end c' of the clip engages the 65 handle at about the curved edge a, which is the best point for holding the fan on the brim when forming an eye shade.

In order to better hold the shank c of the clip C under plate a², I form the plate with 70 a spring tongue a³ which extends inwardly at an incline into the socket formed under the said plate a². This tongue a³ will exert pressure upon the shank c and assist in holding it removably under the plate a².

The fan may be used as such or it may be attached to the brim of a hat, as shown in Fig. 1, where it will form an effective eye shade. The clip may be shaped for brims of different shapes.

80 Referring to Fig. 5, it will be seen that the clip C is secured directly to the handle by means of suitable fastenings, such as the rivets c².

85 What I claim is:

1. A combined fan and eye shade comprising, a fan having a handle provided with a socket near one edge and a spring clip provided with a longitudinally extending shank received within said socket; the said clip 90 adapted to clamp the fan flatwise to the brim of a hat to form an eye shade.

2. A combined fan and eye shade comprising, a fan having a handle provided with a socket in its upper face between its ends, and a spring clip having a shank held in said socket and extending at its free end toward the free end of the handle to clamp the fan to a hat brim parallel therewith.

3. A combined fan and eye shade comprising, a fan having a curved or concaved edge and a handle secured to the fan at the middle of said concave edge, and a spring clip rigidly secured to the fan at one end and extending at its free end toward the said concave edge to clamp the fan to a hat brim parallel therewith.

4. A combined fan and eye shade comprising, a fan having a handle provided with a longitudinal recess in one face, a plate overlying the inner end of said recess to form a socket, and a spring clip having a shank at

its inner end received in said socket and extending at its free end toward the free end of the handle to clamp the fan to a hat brim parallel therewith.

5. A combined fan and eye shade comprising, a fan having a handle provided with a longitudinal recess at its inner end, a plate overlying the inner end of the recess and formed with an inclined spring tongue entering the socket formed by the recess and plate, and a spring clip having a shank held in said recess, the free end of the clip extending toward the free end of the handle to clamp the fan to a hat brim parallel therewith.

10. 6. A combined fan and eye shade for hats comprising, a fan or shade provided with a

rigidly secured clip parallel with its blade or body and adapted to be passed upon a hat brim to hold the fan body parallel therewith. 20

7. A combined fan and eye shade for hats comprising, a fan or shade having a handle, and a rigidly secured clip extending in a direction parallel with the handle and having a shank secured directly upon the upper side of said handle; whereby the clip may be passed upon a hat brim to hold the fan body parallel therewith. 25

In testimony whereof I affix my signature in presence of two witnesses.

ERNEST J. WILLIAMS.
